UNITED STATES PATENT OFFICE.

ANTHONY OSTROSKE, OF DETROIT, MICHIGAN.

KEYLESS LOCK.

1,272,303.

Specification of Letters Patent.

Patented July 9, 1918.

Application filed December 1, 1917. Serial No. 204,951.

To all whom it may concern:

Be it known that I, ANTHONY OSTROSKE, a citizen of the United States, residing at Detroit, in the county of Wayne and State 5 of Michigan, have invented new and useful Improvements in Keyless Locks, of which the following is a specification.

This invention relates to locks capable of being operated without the use of a key.

10 An object of the invention is to provide a lock of the above character which may be operated by persons familiar with its operation without the use of a key, but which cannot be operated by others without first being 15 instructed in its use.

To this end the invention comprehends a novel form of operating means which includes a rotatable disk mounted in the lock casing and normally out of engagement with 20 the locking bolt, the said member being capable of transverse movement with respect to said casing to engage the bolt when in a predetermined position and means located without the casing for determining the position 25 of the rotatable member to effect such engagement.

The invention also consists of the following novel combination and arrangement of parts, to be hereinafter more fully described 30 and illustrated in the accompanying drawings, in which;

Figure 1 is an elevation of a portion of a door with the lock applied thereto.

Fig. 2 is a vertical sectional view of the 35 same showing the rotatable member in elevation.

Fig. 3 is an elevation of the lock removed from the door, one side of the lock casing being also removed, the parts being shown in 40 the position occupied when the bolt is retracted.

Fig. 4 is a similar view with the bolt in its locked position.

Fig. 5 is a perspective view of the operating disk and shank removed from the lock 45 casing.

Referring to the drawings in detail, wherein like characters of reference denote corresponding parts, the reference character 50 A denotes a portion of the door to which the lock, which is of the mortise type has been applied.

The lock, which includes a casing 10 is open at one side, such open side being adapted 55 to be closed by a plate 11, held in position by a screw 12, as is usual in locks of this

character. Mounted within the casing and capable of reciprocating movement therein is a locking bolt 13, the said bolt being guided in its movement by flanges 14 secured to 60 the casing and located at each of the side edges of the bolt, which latter is guided through the usual bolt opening 15, provided in one edge of the casing. The locking bolt 13 is preferably of rectangular formation 65 and extends only a short distance within the casing 10, its inward movement being limited by means of a stop pin 16. Pivotal secured to the bolt 13 as shown at 17, is one end of an arm 18, the opposite end of this 70 arm being formed with an aperture 19 for a purpose hereinafter apparent.

Rotatably mounted within the casing 10 is a disk 20, the said disk having projecting from one face a hub 21, which is mounted in 75 the bearing 22 in one face of the casing 10. The opposite face of the disk 20 carries a hub 23, having formed therein a threaded socket 24 for the purpose of receiving one end of a shank 25. This shank is formed 80 with a spline 26, in which is received a feather 27, one end of the latter entering a notch 28 in the hub 23 of the disk 20 which is adapted to be brought into register with the spline 26 to hold the parts associated. 85 The end of the shank 25 adjacent the hub 23 is provided with an enlargement 29, which has a bearing in an opening 30 formed in the plate 11. The mounting of the disk within the casing 10 is such as to permit of a limited movement thereof transversely of the casing. Carried by the disk 20 is a lug or pin 31, which is adapted to be engaged in 90 the opening 19 formed in the free end of the arm 18.

The disk 20 is normally held from engagement with the arm 18 and for this purpose the shank 25 is provided with a collar 32 and positioned between this collar and a cap 33 is a coiled spring 34, the cap being 100 held in position upon the shank by means of screws or other fastening devices 35 engageable with the escutcheon plate 36 secured to the face of the door. This spring acts to normally force the pin 31 away from the 105 arm 18, so that the disk will be free to rotate without operating the locking bolt. The disk is rotated by means of a knurled finger piece 37 secured upon the outer end of the shank 25. Any desired means may be employed for securing this finger piece to the shank, the means shown consisting of 110

threading the said finger piece upon the shank and locking the same thereon by means of a pin.

In order to hold the arm 18 for engagement by the pin 31 to move the bolt to a locking position, the casing 10 has secured thereto an arm 38 upon which the free end of the arm 18 is adapted to rest, the length of the arm 38 being so regulated that a slight forward movement of the bolt 13 will move the pivoted arm from engagement therewith. The locking bolt 13 carries a rearwardly projecting stop 39, which is adapted to provide a support for the arm 18 when the bolt is in a locking position, so that it may be engaged by the pin 31.

In order to determine the position of the pin 31 so as to move the same into engagement with the arm 18, the cap 33 is provided with suitable indicating characters in the form of numbers, two of which correspond to the two positions of the arm 18 when the latter is at rest. One of these numbers, for example, the numeral 8 will indicate the upper position, so that when the finger piece 37 is rotated to a position to cause the arrow thereon to register with the number 8, the pin 31 will be in position to engage the aperture 19 in the arm 18, this being the unlocked position of the bolt. When the arrow upon the finger piece 37 is brought into register with the numeral 4 the pin 31 will be in position to register with the aperture 19 in the arm 18 when the bolt is in its locking position.

In order to operate the bolt the finger piece 37 is rotated until the arrow registers with the numeral 8, assuming that the bolt is in its retracted position, the said finger piece is then pulled forward, when the pin 31 will enter the opening 19 in the arm 18. The finger piece is then rotated to the left or toward the bolt edge of the lock until it stops, whereupon the finger piece is released and the pin automatically disengaged from the arm 18, leaving the bolt in its locking position. To retract the bolt the finger piece is rotated until the arrow registers with the numeral 4, whereupon the said finger piece is pulled outward causing the pin 31 to engage the opening 19. The finger piece is then rotated to the right as far as possible, thereby retracting the bolt. When this has been accomplished the releasing of the finger piece will automatically disengage the pin from the opening as previously set forth.

It will thus be seen that in order to operate the lock it is necessary to know the particular numbers by means of which the pin 31 may be brought into engagement with the opening 19 and as these numbers may be different upon each individual lock, the knowledge of the combination of one lock will not affect others.

It is believed that from the foregoing de-

scription when read in connection with the accompanying drawings, that the construction, operation and advantages of the invention will be apparent. The right is reserved to make such changes in the form and proportion thereof as will properly fall within the scope of the claims hereto appended.

Having described the invention what is claimed is:

1. The combination of a lock having a locking bolt mounted for reciprocation, of a rotatable member capable of movement transversely of said lock, means including an arm pivotally secured to the bolt and engageable with the rotatable member when the latter is moved transversely of the lock, means for holding the said arm in position for such engagement, means for holding said rotatable member in disengaged position, and means located upon the outside of the lock, whereby the engaging position of the rotatable member and arm may be determined.

2. The combination with a lock having a locking bolt mounted for reciprocation, of a rotatable member capable of movement transversely of said lock, an arm having one end pivotally secured to said bolt, the free end of said arm having an aperture therein, a pin carried by the rotatable member for engagement with the aperture in the arm when the said rotatable member is moved transversely of the lock, means for holding said arm in position for such engagement, means for holding said rotatable member and arm in disengaged position and means located upon the outside of the lock whereby the engaging position of the rotatable member and arm may be determined.

3. The combination with a lock having a locking bolt mounted for reciprocation within a casing, of a rotatable member capable of movement transversely of said casing, a pivoted arm carried by the locking bolt and provided with an aperture, a pin carried by the rotatable member for engagement with said aperture upon transverse movement of the rotatable member, fixed means carried by the casing for holding the arm in position for engagement by the pin when the bolt is retracted, means for holding the arm in position for engagement by the pin when the bolt is in a locking position, means for holding said pin normally disengaged from the arm and means located upon the outside of the casing for predetermineding the pin and arm engaging position.

4. The combination with a lock having a locking bolt mounted for reciprocation within the casing, of a rotatable member capable of movement transversely of said casing, a pivoted arm carried by said locking bolt and provided with an aperture, a

pin carried by the rotatable member for engagement with the aperture upon transverse movement of the rotatable member, means for holding the arm in position for engagement by the pin when the bolt is retracted, a stop carried by the locking bolt and located in the path of the arm for holding the latter in position for engagement by the

pin when the bolt is in a locking position, means for holding said pin normally disengaged from the arm and means upon the outside of the casing for predetermining the pin and arm engaging position. 10

In testimony whereof I affix my signature.

ANTHONY OSTROSKE.
